(57) **CLAIM**

The ornamental design for a sensor for projector, as shown and described.

DESCRIPTION

FIG. 1 is a front, top, and left side perspective view of a sensor for projector;

FIG. 2 is a rear, top, and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines shown in the figures are for the purpose of illustrating portions of the sensor for projector that form no part of the claimed design.

1 Claim, 7 Drawing Sheets
